UNITED STATES PATENT OFFICE.

ADAM OSTHEIMER, OF CLEVELAND, OHIO.

RAILWAY CONSTRUCTION.

1,077,548.

Specification of Letters Patent.

Patented Nov. 4, 1913.

Application filed January 20, 1913. Serial No. 743,072.

To all whom it may concern:

Be it known that I, ADAM OSTHEIMER, a citizen of the United States, residing at Cleveland, in the county of Cuyahoga and 5 State of Ohio, have invented a new and useful Improvement in Railway Constructions, of which the following is a specification, the principle of the invention being herein explained and the best mode in which I have 10 contemplated applying that principle, so as to distinguish it from other inventions.

My invention has general reference to a railway construction, and more particularly to specific improvements upon that shown, 15 described and claimed in United States Letters Patent No. 1,036,891, issued to me on August twenty-seventh, nineteen hundred and twelve.

The object of the invention is to provide 20 a construction of the character stated which shall prove more efficient by reason of being yieldingly responsive to and hence tend to compensate for wear and tear.

More specifically the object is to insure 25 a more permanent structure as regards the fixed relation of its parts, whereby constant periodical attention heretofore required may no longer be necessary, and yet avoid undue rigidity.

30 The inventive conception is embodied in means which are hereinafter explained and variously combined in the claims, while the annexed drawing and particular description thereof together set forth in detail one certain means constituting my invention, the 35 disclosed means however, being but one of various mechanical forms in which the principle of my invention may be applied.

In the drawing: Figure I is a part elevation, part section of a railway construction embodying my invention. Fig. II is an enlarged view more clearly showing one detail. Fig. III is an elevation of a portion of one side of the structure. Fig. IV is a perspective view of one detail. Fig. V is a perspective view of a preferred fastening or locking contrivance.

50 My construction comprises a plurality of properly spaced underlying ties 1 which according to my inventive conception are of T shaped cross-section so that the flat upper surfaces 2 project laterally in both directions as is clearly indicated in Fig. 3. The under edges of the ties designed after the 55 manner of my invention present moreover a convex curve 3 for a purpose to be herein-

after explained. The middle upper sections of the ties are furthermore depressed to assume a concavely formed surface 4 as is clearly apparent from an inspection of 60 either Fig. 1 or 2.

Superimposed upon each of the ties 1, and preferably of a size corresponding with the dimensions of the upper surfaces thereof, are a plurality of straight flat plates 5, 65 which, accordingly span the depressed central portion of the ties. Supported upon opposite ends of the plates 5 and indirectly therefore upon the ties 1 are a pair of transversely extending beams 6. These beams are 70 of approximately inverted U shape and are adapted to support upon their horizontal web portion the rails 7. A fixed relation between the ties 1, plates 5, beams 6 and rails 7 is simultaneously established through the 75 medium of clips 8 and lock-nut contrivances 9. A more precise explanation of this superstructure or direct rail-supporting structure may be dispensed with since it corresponds with that shown, described and 80 claimed in my patent above referred to.

My present inventive conception furthermore includes the insertion of a plurality of separate supports 10 adapted to be snugly interposed between the under-surface of the 85 web portion of the beam 6 and that upper surface of the plates 5 which is in vertical alignment therewith. These supports are preferably though not necessarily of I shaped cross-section as clearly appearing in 90 Fig. 4 and as such comprise an upright portion 11 and the two substantially horizontal portions 12 and 13. I choose to make the lower portion 13 of somewhat greater width and itself of channel cross-section, so as to 95 comprise downwardly projecting edge flanges 14. The dimensions of the channel thus formed should be such that it will afford a close mechanical fit with the lateral edges of the plates 5. These supports 10 are 100 accordingly intended to afford an added measure of safety and while they do increase the rigidity at the points of insertion, this is more than offset by the resilience elsewhere effected through the medium of my 105 specific design of tie.

The distribution if not dissipation of stress in a railway construction built in accordance with my invention is such that all downward thrusts, resulting from the reaction of the springs upon the coaches which are intended to travel upon the rails,

will be immediately and in proper measure responded to by a part rocking, part yielding action of the part of the ties due to their design. Ties of the character described will 5 compensate for downward thrusts of different degrees upon oppositely disposed rail portions or oppositely disposed ends of the ties. Their particular formation also permits of a more gradual movement with respect to the road-bed and incidentally with 10 a minimum of damaging or disrupting effect upon the same. The comparatively thin under edge of the tie is obviously less likely to occasion the displacement of a sufficient portion of the road-bed as will necessitate early attention, by reason of causing 15 a sagging of one portion of the track as a whole with respect to another. The upper portion of the ties by reason of their lateral 20 projections in the meantime coöperate by also tending to preclude a sagging on the part of the ties, while the medial depressions extending only between the inner edges of the rail supports proper contribute 25 toward the resiliency demanded.

My invention being thus described with sufficient thoroughness, what I desire to secure by Letters Patent and therefore claim specifically, is:

30 1. A railway construction comprising the combination of a plurality of ties formed with a concavity intermediately of their ends, a corresponding number of plates overlying said ties respectively and spanning such concavity, transversely extending rails, and means for fixing said ties, plates and rails relative to each other.

2. A railway construction comprising the combination of inverted U shaped beams, 40 rails thereon and extending parallel therewith, a plurality of underlying ties extending transversely of said beams, and a separate support of I shaped cross-section snugly interposed between each beam and tie, the web portion of said supports likewise extending transversely of said beams, and means for fixing said rails, beams, supports and ties relative to each other.

3. A railway construction comprising the 50 combination of a pair of rail supporting members, a plurality of underlying ties ex-

tending transversely thereto and formed with a concavity intermediately thereof, transverse plates interposed between said members and ties and spanning said concavity, and means for fixing said members, plates and ties with relation to each other. 55

4. A railway construction comprising the combination of a pair of rails, a plurality of underlying ties of T shaped cross-section and depressed centrally, plates interposed between said rails and ties and spanning said depressions, and means for fixing said rails, plates and ties relative to each other. 60

5. A railway construction comprising the combination of a plurality of ties, beams having concave under sides transversely supported upon said ties, rails upon said beams, means for fixing said ties, beams and rails with respect to each other, and separate supports seated within said beam concavities and themselves provided with concave under sides adapted to inclose said ties. 65

6. A railway construction comprising the combination of a plurality of ties of T shaped cross-section, inverted U shaped beams transversely supported upon said ties, rails upon said beams, means for fixing said ties, beams and rails with respect to 70 each other, and separate supports disposed within said beams and resting upon said ties.

7. A railway construction comprising the combination of a plurality of ties of T shaped cross-section, and having their middle portions concave, plates overlying said ties and spanning said concavities, inverted U shaped beams transversely supported upon opposite ends of said plates, rails upon said beams, means for simultaneously fixing said ties, plates, beams and rails with respect to each other, and separate supports of I shaped cross-section disposed underneath said beams and resting upon respective of 95 said ties.

Signed by me, this 15th day of January, 1913.

ADAM OSTHEIMER.
